United States Patent Office.

JOHN C. REYNOLDS, OF TAUNTON, MASSACHUSETTS.

Letters Patent No. 70,360, dated October 29, 1867.

IMPROVED KNIFE-SHARPENER.

The Schedule referred to in these Letters Patent and making part of the same.

TO ALL WHOM IT MAY CONCERN:

Be it known that I, JOHN C. REYNOLDS, of Taunton, in the county of Bristol, and State of Massachusetts, have invented a new and useful Improvement in Knife-Sharpener; and I do hereby declare that the following is a full, clear, and exact description thereof, reference being had to the accompanying drawings, making a part of this specification, in which—

Figure 1 is a perspective view.

Figure 2 the same, with a knife in the proper position to be sharpened; and

Figure 3 showing another method of securing the tool or machine when in use.

A is the bed-piece or frame, B the clamp, T the thumb-screw, C C the sharpeners or "steels," and D D screws to secure the machine to a table, when the clamp and thumb-screw are not used. Into any piece of metal of the desired size and thickness, as shown at A, I drill two holes (to receive the "steels") at the same angle with each other as I may desire to give to the edge of the knife when used, as shown in fig. 2. Into these holes I screw the "steels" or sharpeners C C. These sharpeners are made of steel, round or cylindrical, and fluted or "milled" longitudinally. They are of such a length as to form, when screwed into the frame A, a figure somewhat resembling the letter X. As these "steels" become worn, a new surface is presented for use by giving them a slight turn by means of a wrench used upon the ends S S, which are made square for this purpose. The plate of metal or frame A may be secured to the table or bench by any method practicable. One method is shown at fig. 1, another at fig. 3.

I claim as a new article of manufacture—

A knife-sharpener, with two steels arranged to turn in a stand, and present new sharpening surfaces when required, in combination with said stand and a foot and clamping-screw to fasten it to a shelf or table, substantially as described.
